(57) CLAIM

The ornamental design for [an umbrella] a parasol [for patio or beach use], as shown and described.

DESCRIPTION

FIG. 1 is a side perspective view of [an umbrella] a parasol [for patio or beach use] showing my new design in condition of use with a curved pole and stand; and, FIG. 2 is a front perspective view thereof shown in condition of use with an ornamental endcap, partial pole and crankshaft. The broken [line showing of an] lines depicting the ornamental endcap, pole, stand, and crankshaft [is] are for illustrative purposes only and [forms] form no part of the claimed design.

1 Claim, 2 Drawing Sheets

Matter enclosed in heavy brackets [ ] appears in the original patent but forms no part of this reissue; matter printed in italics indicates the additions made by reissue.
